UNITED STATES PATENT OFFICE.

FREDERICK M. LEUSCH, OF TOLEDO, IOWA, ASSIGNOR TO THOMAS O. AXTELL, OF TOLEDO, IOWA.

RIDING HARROW-CART.

No. 796,135.

Specification of Letters Patent.

Patented Aug. 1, 1905.

Application filed April 10, 1905. Serial No. 254,844.

To all whom it may concern:

Be it known that I, FREDERICK M. LEUSCH, a citizen of the United States, residing at Toledo, in the county of Tama and State of Iowa, have invented a new and useful Riding Harrow-Cart, of which the following is a specification.

This invention relates to sulkies or carts forming riding attachments for harrows; and it has among its objects to simplify and improve the construction and operation of the same.

Another object of the invention is to present a riding or sulky attachment which may be used with great advantage in connection with drag-harrows of ordinary construction.

Another object is to provide for the convenient turning of the device at the corners of the field and in such a manner that the sulky shall follow directly in rear of the harrow.

With these and other ends in view, which will readily appear as the nature of the invention is better understood, the same consists in the improved construction and novel arrangement and combination of parts, which will be hereinafter fully described, and particularly pointed out in the claims, reference being had to the accompanying drawings, in which—

Figure 1 is a top plan view showing a drag-harrow of ordinary construction to which the improved riding attachment has been applied. Fig. 2 is a longitudinal vertical sectional view of the same. Fig. 3 is a perspective detail view of a portion of the riding attachment. Fig. 4 is a top plan view illustrating a modification.

Corresponding parts in the several figures are indicated throughout by similar characters of reference.

In the construction of this device is employed an axle 1, which, as shown in the drawings, may be a round iron bar, or it may, if preferred, consist of a tube of suitable dimensions. Suitably supported upon said axle are uprights 2 2, provided with bases 3 3, the under sides of which are provided with axle-engaging concavities or recesses 4 4, and the outer ends of which are provided with flanges 5, forming dust-caps for the hubs of the wheels 6. The uprights are secured upon the axle by means such as bolts 7, and said uprights are provided at their upper ends with inwardly-ex-

tending brackets 8, connected by means of a cross-piece, such as an angle-bar 9, which is supported upon the brackets 8 and connected with the latter by means of bolts 10.

Pivotedly connected with the axle 1 by means of pins or bolts 11, which are in axial alinement with the bolts 10, are frame-bars 12 13, which extend forwardly from the axle, crossing each other, as clearly shown in Fig. 1, one of said frame-bars 12 being provided with a raised offset or arched portion 14 for the accommodation of the frame-bar 13. In order to strengthen the construction, the frame-bars 12 13 are connected with the brackets 8 of the uprights 2 by means of inclined braces 15, the upper ends of which pivotally engage the bolts 10. The lower ends of the braces 15 are connected with the frame members 12 and 13 by means of bolts or pivotal connecting members 16, which also serve for the attachment of a cross-brace 17, which latter is provided near one end with a slot 18, slidably engaging the connecting bolt or pin. The cross-brace 17 also serves as a foot-rest for the driver, whose seat 19 is supported upon a bow-spring 20 at the upper end of an upright 21, which is connected by means of a bolt 22 with the vertical web of the angle-bar 9 and by means of a clip 23 with the axle 1.

The front ends of the frame members 12 13 are connected pivotally with a draft-bar 24, a harrow 25 of ordinary construction being connected with said draft-bar by means of links 26 or flexible connecting means of any suitable character. The harrow illustrated in the drawings has been shown as comprising side members 27 and pivoted cross-bars 28, having teeth 29, said cross-bars being provided with brackets 30, connected by a rod 31, which in its turn is connected with and operated by a hand-lever 32, whereby the harrow-bars may be tilted for the purpose of discharging trash accumulated thereby. It is to be understood, however, that a harrow of any other suitable construction may be used in connection with the improved riding attachment.

From the foregoing description, taken in connection with the drawings hereto annexed, the operation and advantages of this invention will be readily understood by those skilled in the art to which it appertains. It will be

readily seen that draft applied to the draft-bar 24 will be transmitted directly to the harrow and also to the axle of the sulky. The draft is transmitted to the sulky through the medium of the crossing frame-bars 12 13, so that when a turn is made the outside wheel will be caused to make a long turn, while the inside wheel will make a short turn, thus causing the sulky to follow directly in rear of the center of the harrow. The draft will be light, and the harrow may be easily manipulated and regulated.

The sulky-frame may be easily disconnected from the harrow, and the parts of the device may be readily assembled or disconnected, as may be desired.

The construction of this improved device is extremely simple and efficient. The material preferably employed in the construction is iron and steel, angle-irons being preferred wherever available.

While I have in the foregoing described a simple and preferred construction of the device, it is desired to be understood that no limitation is necessarily made to the precise structural details illustrated in the drawings and referred to in the foregoing specification, but that changes, alterations, and modifications may be made within the scope of the invention and without departing from the spirit or sacrificing the efficiency of the same.

Under the modification illustrated in Fig. 4 of the drawings one of the frame-bars (here designated 13') is provided with a lateral offset or curved portion 14', which extends from its point of attachment to the axle in the direction of the opposite end of the axle, said offset being of sufficient dimensions to cause the frame-bars 12' and 13' to intersect or cross each other at a point very close to the axle. The upwardly-offset portion (here designated 14^b) of the frame-bar 12 is located close to the axle and directly above the laterally-offset portion 14' of the frame-bar 13'. By this construction the intersecting portion of the cross-bars will be disposed to one side of the longitudinal center of the machine, and the harrow-lever 32 may be placed to one side of the crossing or intersecting frame-bars, where it is more readily accessible to the driver and less liable to be interfered with by the frame-bars in the act of turning corners. Under this construction the cross-bar 17 is dispensed with and a foot-rest 15^b is clamped upon the upwardly-offset portion 14^b of the frame-bar 12'.

Having thus described the invention, what is claimed is—

1. An axle, uprights supported upon said axle and having inturned brackets at their outer ends, a cross-bar supported upon said brackets, connecting members securing the cross-bar upon the brackets, frame-bars connected pivotally with the axle by means in axial alinement with the aforesaid connecting

members, and braces connected with the frame-bars and extended to and pivotally connected with said connecting members.

2. An axle, frame-pieces pivotally connected therewith, uprights supported upon the axle and having inwardly-extending brackets, a cross-bar supported upon said brackets, braces extending from the pivoted frame-pieces to the under sides of said brackets, and pins or bolts connecting said braces and cross-bar with said brackets; said pins or bolts being in axial alinement with the pivots of the frame-pieces.

3. An axle, frame-pieces connected pivotally therewith and crossing each other, one of said frame-pieces being provided with an offset or arched portion, a draft-bar connected pivotally with the front ends of said frame-pieces, and a cross-bar connected pivotally with one frame-piece and slidably with the other frame-piece, said cross-piece constituting a foot-rest.

4. An axle, uprights upon said axle, a cross-bar connecting said uprights, a seat-supporting member connected with said cross-piece and with the axle, frame members connected pivotally with the axle and crossing each other, braces connected with said frame members and also connected pivotally with the uprights upon the axle, a draft-bar pivotally connected with the front ends of the frame-pieces, and a cross-bar connected with one frame member and constituting a foot-rest.

5. An axle having an arch, a seat-supporting member connected with said axle and arch, frame members connected pivotally with the axle, a cross-bar connected pivotally with one frame member and slidably with the other frame member, a draft-bar connected pivotally with the front ends of the frame members, and a harrow connected flexibly with the draft-bar.

6. A riding attachment for harrows including a wheel-supported axle, uprights upon said axle, a cross-bar connected with said uprights, a seat-supporting member connected with said cross-bar and with the axle, frame members having inclined braces said frame members and braces being pivotally connected with the axle and with the uprights by means in axial alinement with each other, and said frame-bars being disposed across one another; a draft-bar connected pivotally with the front ends of the frame members, one of said frame members having an arched portion for the accommodation of the other frame member; and a harrow flexibly connected with the draft-bar.

7. An axle, frame-pieces connected pivotally therewith and crossing each other, one of said frame-pieces being provided with a laterally offset or curved portion and the other frame-piece having an upwardly offset or arched portion at the point of intersection.

8. An axle, frame-pieces connected pivot-

ally therewith and crossing each other, one of said frame-pieces being provided with a laterally offset or curved portion and the other frame-piece having an upwardly offset or arched portion at the point of intersection; and a foot-rest supported upon said arched portion.

9. An axle, frame-pieces connected pivotally therewith and crossing each other, one of said frame-pieces being provided with a laterally offset or curved portion and the other frame-piece being provided with an upwardly offset or arched portion at the point of intersection, a draft-bar connected pivotally with the front ends of the frame members, and a harrow connected flexibly with the draft-bar.

10. A riding attachment for harrows in-

cluding a wheel-supported arched axle, crossed members connected pivotally with the axle, and a draft-bar connected pivotally with the front ends of said crossed members; one of the latter being provided near the axle with a curved or offset portion extending in the direction of the opposite end of the axle and the other member being provided with an upwardly-arched portion accommodating the laterally-offset portion of the first member.

In testimony that I claim the foregoing as my own I have hereto affixed my signature in the presence of two witnesses.

FRED. M. LEUSCH.
